H. Weed

Bonnet.

N° 11186

Patented Jun. 27, 1854.

Fig. 1.

Fig. 2.

UNITED STATES PATENT OFFICE.

HENRY WEED, OF PHILADELPHIA, PENNSYLVANIA.

MODE OF CONSTRUCTING WIRE BONNET-FRAMES.

Specification of Letters Patent No. 11,186, dated June 27, 1854.

To all whom it may concern:

Be it known that I, HENRY WEED, of Philadelphia, in the county of Philadelphia and State of Pennsylvania, have invented a 5 new and Improved Mode of Forming Wire Frames or Shapes for Bonnets; and I do hereby declare that the following is a full and exact description thereof, reference being had to the accompanying drawing and 10 to the letters of reference marked thereon.

Figure 1 represents the front view, and Fig. 2 represents the plan of my improved method of forming wire frames for bonnets.

The drawing is half size, or 6 inches to 15 the foot.

My invention consists in a new and improved mode of forming wire frames for bonnets, by which I accomplish the reduction of the cost and produce wire frames of 20 a more uniform size and shape. This I effect by placing perpendicular pins or stays on a plate or board, in suitable positions for the design or form required, and around which the wire is wound and thereby 25 formed.

Wire frames for bonnets have been formed heretofore, by bending the wire (which generally has to be doubled) by hand, and stitched on buckram or stiffened 30 cloth, that has the design marked thereon. While fixed to the buckram suitable cross stays (also made of wire and formed by hand) are stitched firmly to the frame for the purpose of securing the parts together. 35 The thread which secures the wire frame to the buckram is then cut and drawn out. The bending of the wire (which is covered by silk or other thread) is a very difficult operation, even to those who may have had 40 considerable experience in the business. By the use of my improved apparatus any person who can use a thread and needle may make a merchantable bonnet frame, in much less time and with greater accuracy, than 45 could be done by the old process.

A represents a board or plate having a number of perpendicular pins or stays B fixed thereon. The position of said pins or stays B depends altogether upon the size and shape of the frame required. 50

The wire D is first cut the proper length, then doubled, and wound around the outside of the pins B (which form the large semicircle) and then around the top of pins B which form the lesser semicircle, (as indicated by blue lines on the drawing), and rests in grooves or spaces formed on the sides and tops of said pins B. The wire D is thereby brought to the required form. The cross-stay wire C is then wound around 55 the top of said pins B and crossed over from one semicircle to the other, and is then secured to the wire D first formed by stitching them together. The wire frame may then be taken off the pins B, and will retain its 60 shape.

By the above described means, any number of wire frames for bonnets can be formed precisely the same shape and size. 65

The pins or stays B may be fixed permanently to the plate A, or they may be so arranged that they may be adjusted, so that the size and shape of the wire frames may be varied at pleasure. 70

Having now fully described the nature of 75 my invention and explained the mode of operation, what I claim as my invention, and desire to secure by Letters Patent, is—

The method herein described of forming wire frames for bonnets, viz. by winding 80 the wire around pins or stays, or their equivalents arranged substantially as described on a plate or board thereby securing uniformity and exactness, in every particular, as specified.

HENRY WEED.
